UNITED STATES PATENT OFFICE.

AUGUSTUS W. AVERY, OF COVE, NORTH CAROLINA.

RAIL-FASTENING.

No. 856,835.

Specification of Letters Patent.

Patented June 11, 1907.

Application filed September 26, 1906. Serial No. 336,273.

To all whom it may concern:

Be it known that I, AUGUSTUS W. AVERY, a citizen of the United States, and a resident of Cove, in the county of Craven and State of North Carolina, have invented certain new and useful Improvements in Rail-Fastenings, of which the following is a specification.

My invention is an improvement in rail fastenings, and consists in certain novel constructions and combinations of parts as will be hereinafter described and claimed.

In the drawing Figure 1 is a top plan view of the invention. Fig. 2 is a cross-section on about line 2—2 of Fig. 1. Fig. 3 is a detail top plan view of a portion of the tie. Fig. 4 is a detail vertical section illustrating the application of one of the bolts to its slot in the tie, and Fig. 5 is a detail view illustrating the application of the other bolt to its tie slot.

20 The tie A is adapted to receive the rail B and may be provided at its side edges with the depending flanges A', as will be understood from Fig. 2 of the drawing. The rail B rests flat upon the tie between the opposite slots C and D, the slots D being preferably arranged in pairs, as will be understood from Figs. 1 and 3 of the drawing. These slots C and D receive the bolts E and F for holding the clamp plates G and H, as shown in Figs.

30 1, 2 and 3. Ordinarily the clamp plate H is arranged at the outer side of the rail and the clamp plate G at the inner side of the rail so for convenience of reference I will refer to the plates H and G, respectively, as the outer and inner clamp plates. These clamp plates are recessed in their inner sides at h and g to receive the base of the rail B and are extended at their ends at h' and g' to bear against the web of the rail and thus insure the holding of

40 the rail by the clamp plates even should the bolts become so loosened as to permit the shoulders at h² and g² to ride above the outer edges of the rail base so that the clamp plates will operate to secure the rails as long as said plates are held by their bolts whether the nuts be tight or loose.

The bolts E are secured in the slots C and the bolts F in the slots D and these slots are provided at one end with enlarged portions C' and D' to receive the heads of the bolts and said slots are elongated in a direction at a right-angle to the rail and the enlarged portions C' and D' of the slots are at the corresponding ends of their respective slots, so 55 that when the bolts are inserted the reduced

or smaller ends of the slots are at the outer ends thereof with respect to the outer side of the track so that the bolts will be held as against any tendency by the spreading of the rail against adjustment to the enlarged ends 60 of their respective slots. The bolt E has its head E' adapted to be inserted through the enlarged portion C' of the slot C and the shank of the bolt adjacent to the head E' is squared at E² with its square of such size as 65 to permit it to be moved along the slot C and its diagonals of such length as to permit the bolt to fit at its corners in notches C² in the opposite sides of the slot C when the bolt is so turned as will be understood from Fig. 3 of 70 the drawing, so that when in this adjustment the bolt will be locked from movement within the slot as will be understood from Fig. 3 of the drawing. Ordinarily I provide several notches C² so the bolt may be secured at 75 different points within the slot C as desired. This bolt E extends up through the clamp plate G and thence through a washer G' upon said clamp plate and receives the nut e as shown in Figs. 1 and 2 of the drawing. In 80 Fig. 5, I show the bolt in dotted lines as inserted through the enlarged portion C' of the slot C and in full lines as held within the slot C by the fitting of its corners in the notches in the said slot, as will be understood from 85 Figs. 3 and 5.

The slot D has its enlarged portion D' in the form of a semicircle, this semicircular end D' permitting the insertion of the head F' of the bolt F when the latter is turned to inclined position, as shown in Fig. 4, after which the bolt may be adjusted along the slot D to the position indicated in dotted lines in Fig. 4, and then passed up through the opening H² in the clamp plate H, thence 90 through the washer H' and be secured by the nut f as shown in Figs. 1 and 2.

The outer walls of the openings H² in the plate H are preferably inclined, as shown, to facilitate the application of the clamp plate to the bolts in applying said plate to its engagement with the rail. The enlarged semicircular portion D' of the slot D has its rounded side sloped at d' to facilitate the introduction of the bolt head, as best shown in 95 Figs. 2 and 4.

What I claim is—

1. The combination with the rail and the clamp plate G, of a bolt E and a tie having a slot notched in its opposite walls to receive 100

the corners of the bolt shank whereby to lock the bolt when applied to secure the clamp plate, substantially as set forth.

2. The combination with the rail, the 5 clamp plate and the bolt for securing the same, of a tie plate having a slot receiving said bolt and provided with an enlarged semicircular end portion for the introduction

of the bolt head, the rounded side of said enlarged portion being sloped to facilitate the 10 introduction of the head, substantially as set forth.

AUGUSTUS W. AVERY.
